HANGER FOR SUPPORTING A BALANCED ARTICLE

Duane W. Bacon, Jr., 6743 Candlewood Trail,
Birmingham, Mich. 48010

Filed Feb. 26, 1971, Ser. No. 119,448

Term of patent 7 years

Int. Cl. D21—01
U.S. Cl. D34—15

Fig-1

Fig-3

Fig-2

Fig-4

Fig-5

Fig-6

FIG. 1 is a perspective view of a hanger for supporting a balanced article showing my new design;

FIG. 2 is a view thereof as seen from one side, the opposite side being substantially a mirror image thereof;

FIG. 3 is a view as seen from the top side of FIG. 2;

FIG. 4 is a view as seen from the bottom side of FIG. 2;

FIG. 5 is a view as seen from the right side of FIG. 2; and

FIG. 6 is a view as seen from the left side of FIG. 2. I claim:

The ornamental design for a hanger for supporting a balanced article, as shown and described.
